(57) **CLAIM**

The ornamental design for a support beam for screened enclosure, as shown and described.

DESCRIPTION

FIG. 1 is a front perspective view of a first embodiment of a support beam for a screened enclosure;

FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is a front perspective view of a second embodiment of a support beam for a screened enclosure;
FIG. 9 is a front view thereof, the rear view being a mirror image;
FIG. 10 is a front perspective view of a third embodiment of a support beam for a screened enclosure;
FIG. 11 is a front view thereof, the rear view being a mirror image;
FIG. 12 is a front perspective view of a fourth embodiment of a support beam for a screened enclosure;
FIG. 13 is a front view thereof, the rear view being a mirror image;
FIG. 14 is a front perspective view of a fifth embodiment of a support beam for a screened enclosure;
FIG. 15 is a front view thereof, the rear view being a mirror image;
FIG. 16 is a front perspective view of a sixth embodiment of a support beam for a screened enclosure;
FIG. 17 is a front view thereof, the rear view being a mirror image;
FIG. 18 is a front perspective view of a seventh embodiment of a support beam for a screened enclosure;
FIG. 19 is a front view thereof, the rear view being a mirror image;
FIG. 20 is a front perspective view of an eight embodiment of a support beam for a screened enclosure;
FIG. 21 is a front view thereof, the rear view being a mirror image;
FIG. 22 is a front perspective view of a ninth embodiment of a support beam for a screened enclosure;
FIG. 23 is a front view thereof, the rear view being a mirror image;
FIG. 24 is a front perspective view of a tenth embodiment of a support beam for a screened enclosure; and,
FIG. 25 is a front view thereof, the rear view being a mirror image.

(Continued)

The support beam for screened enclosure is shown with a symbolic break in its length. The appearance of any portion of the article between the break lines forms no part of the claimed design.
